(57) **CLAIM**

The ornamental design for a theft prevention device, as shown and described.

DESCRIPTION

FIG. 1 is a perspective view of a theft prevention device showing my new design;

FIG. 2 is a front view thereof;

FIG. 3 is a left side view thereof, the right side view being a mirror image;

FIG. 4 is a rear view thereof;

FIG. 5 is a top view thereof;

FIG. 6 is a bottom view thereof; and,

FIG. 7 is an exploded perspective view thereof, shown in an unassembled state.

Environmental features shown in broken lines are for illustrative purposes only and form no part of the claimed design.
